UNITED STATES PATENT OFFICE.

GANO S. DUNN, OF EAST ORANGE, NEW JERSEY, ASSIGNOR TO THE CROCKER-WHEELER COMPANY, OF NEW JERSEY.

MULTIPLE-VOLTAGE CONTROLLER.

SPECIFICATION forming part of Letters Patent No. 662,375, dated November 20, 1900.

Application filed March 21, 1900. Serial No. 9,586. (No model.)

To all whom it may concern:

Be it known that I, GANO S. DUNN, a citizen of the United States of America, and a resident of East Orange, in the county of Essex and 5 State of New Jersey, have invented certain new and useful Improvements in Multiple-Voltage Controllers, of which the following is a specification.

This invention provides means by which a 10 working motor may be connected to either of several conductors, which are maintained at different voltages and regulated when so connected. The purpose is to enable the motor to be run efficiently at either of several speeds. 15 This means consists in a controller by which the motor is started and a multiple-voltage switch by which the motor-armature is connected to conductors of the voltage requisite for the desired speed. Between the controller 20 and the multiple-voltage switch are interlocking devices by which the operation of the multiple-voltage switch is prevented except when the controller is in the open or off position, and the movement of the controller from the 25 open position is prevented when the multiple-voltage switch is intermediate between any of the points at which it effects connections.

In the accompanying two sheets of drawings, which form a part of this specification, 30 Figure 1 is a diagrammatic representation of the system, including the controller and multiple-voltage switch. Fig. 2 is a top view of the controller and multiple-voltage switch. Fig. 3 is a vertical cross-section on the line x^3 of Fig. 2. Fig. 4 is a vertical cross-section on the line $x^4 x^4$ of Fig. 3.

As shown in Fig. 1, the controller and multiple-voltage switch receive current from five conductors, which are maintained at different 40 voltages. Thus, for example, if conductor 1 be taken as the positive main then with respect to this conductor conductor 2 will be maintained at one hundred and fifty-two volts, conductor 3 at one hundred and eighty-six volts, conductor 4 at two hundred and twenty volts, and conductor 5 at two hundred and fifty-four volts. These conductors are maintained at these voltages by a dynamo-electric machine or generator 6, which is 45 driven by any suitable source of power, and a four-armature dynamotor. The dynamo has

a compound field and is connected to the conductors 1 and 4 through a circuit-opening switch 7. It maintains the conductors between which it is connected at a difference of 55 potential of two hundred and twenty volts. The fields 8 of all the dynamotor-armatures are supplied from the conductors 1 and 4, and the driving dynamotor-armature 9 is also supplied from these conductors. The second 60 dynamotor-armature 10 is connected between the conductors 2 and 3, the third armature 11 is connected between the conductors 3 and 4, and the fourth armature 12 is connected between the conductors 4 and 5. Each of 65 these armatures maintains the pair of conductors between which it is connected at a difference of potential of thirty-four volts. The differences in potential with respect to lead 1 are, in consequence, as above stated. 70 It is not, however, essential to my combined multiple-voltage switch and controller that the differences in potential should be as above indicated or that they should be maintained upon the conductors by any particular combination of dynamos and dynamotors, and the invention is equally applicable in a system in which either a greater or a fewer number of 75 different voltages are employed; but as the invention depends on the employment of a 80 plurality of voltages it is essential that there should be at least three conductors and that suitably-driven armatures or other suitable sources of electrical energy should be so connected between the conductors that all will 85 be interconnected, and if a motor be connected between any two conductors a current will flow through the motor from one conductor to the other and the circuit will be completed through one or more of the interconnecting armatures. These armatures may be 90 grouped between the conductors in a variety of ways, and the arrangement may or may not be such that the potential on some conductors will result from a reduction of the 95 potential by means of motors from other conductors on which a higher potential is maintained. Thus, for example, the current on conductor 2 is maintained at one hundred and fifty-two volts with respect to conductor 1; 100 but it is derived from conductor 4, which is maintained at two hundred and twenty volts

with respect to conductor 1. The reduction is effected by means of the armatures 10 and 11, which act as motors to reduce the potential.

In the form illustrated wires from the conductors 2, 3, 4, and 5 are led to four contact-plates 13 of the multiple-voltage switch. The switch-lever 14 of this switch according to its position connects one or the other of these contacts with a plate 15. From this plate a wire leads to one of the blades 16, and from conductor 1 a wire leads to one of the blades 17 of a three-blade main switch, by which the connections are made between the conductors and the multiple-voltage switch on the one hand and the working motor and the controllers on the other hand. The middle blade 18 connects the shunt-field of the working motor with one of the main conductors 4. The three blades of this switch are insulated from each other, but are mechanically connected, and are opened and closed by a single handle.

The controller is a cylinder with several groups of raised contact-plates, the plates of each group being in electrical connection, but insulated from the plates of other groups on the same side. For convenience of diagrammatic representation the controller is shown in Fig. 1 as a flat sheet of insulating material, with contact-plates supported thereon. The sheet is moved transversely either to the right or to the left from the open or off position in which it is shown to bring the contact-plates under the contact-fingers and effect the electrical connections. When this is done, the main circuits are from the conductor 1 through the blade 17 to a contact-finger 19, through the left or right group of plates 20, accordingly as the controller is moved to the right or to the left, through all of the resistance 21, if contact is made with the contact-finger 22, or more or less of the resistance, if contact is made with either of the contact-fingers 23, 24, 25, or 26, or around all of the resistance, if contact is made with contact-finger 27. From the resistance or around the resistance, if the controller is moved to the left, the circuit is through the contact-finger 28, plates 29, contact-finger 30, through the armature 31 of the working motor, contact-finger 32, and plates 33 to the contact-finger 34. If the controller is moved to the right, the circuit from the contact-finger 28 is through the plates 35, contact-finger 32, through the armature in the opposite direction to contact-finger 30, and contact-plates 36 to contact-finger 34. From contact-finger 34 the circuit is through the series field 37 of the working motor and thence through the blade 16 to the plate 15, through the contacts carried by the multiple-voltage switch-lever to one or the other of the contacts 13, according to the position of this lever, to one or the other of the conductors 2, 3, 4, or 5, thereby completing the circuit through the armatures of the dynamotor and the dynamo back to conductor 1. It will be

seen, therefore, that the controller in addition to being an ordinary rheostat for varying the resistance in circuit with the motor is also a reversing-switch for reversing the direction of the current through the armature of the working motor. It is not essential to this invention that the controller should have this latter feature. There is also a second circuit which is through the shunt-field 38 of the working motor. This is closed as the controller is moved in either direction from the off position. This circuit branches from the main circuit at the contact-finger 22 and leads through the shunt-field and blade 18 to one of the conductors 4. This circuit is independent of the position of the multiple-voltage switch and the amount of resistance cut out by the controller. It will thus be seen that the working motor has a compound field, one part being in series with the armature and the other in shunt with the armature. The series-field coil can be connected through the multiple-voltage switch to conductors of different potential, and the shunt-field is connected always to the same conductors.

For the convenience of diagrammatic illustration the interlocking device between the multiple-voltage switch and the controller, as illustrated in Fig. 1, is somewhat different from the interlocking device which is actually employed, as shown in Figs. 2, 3, and 4; but the mechanical result is the same and will be understood without further description from an explanation of the device as actually used.

The actual construction of the multiple-voltage controller is shown in Figs. 2, 3, and 4. The casing for it is made in two compartments. The one at the left in Fig. 4 contains the multiple-voltage switch, and the one at the right contains the controller. The controller is carried by a vertical shaft. Mechanically attached to this shaft, but insulated therefrom and from each other, are a series of metal sleeves with raised segments corresponding to the groups of contact-plates described in the discussion of the diagram and indicated in these figures by the same reference-numerals. A wooden block supports the contact-fingers. The controller is operated by the handle 40. Attached to the controller-shaft is a disk 41, with a notched periphery, which is engaged by a roller 42 on the end of a lever 43, which is pressed against the disk by the spring 44. The notches are so placed that they will come opposite the roller when the contact-plates are in positions to make good electrical contacts with the contact-fingers.

The multiple-voltage switch is pivoted to a plate 45, of insulating material, on which the contact-plates 13 and 15 are mounted. Fingers 46 and 47 are carried by the switch-lever and connect the contact-plates. The switch-lever is a spring-blade which passes through a slot in the top of the casing. The blade

springs into notches 48 in one side of the slot when in each of the operative positions. The lever plays over the face of a hinged locking-plate 49, which lies on the opposite side of the blade from the notches in the slot. This plate is pressed against the lever by one end of a spring-pressed latch 50. The opposite end of the latch engages a notch in a disk 51 on the controller-shaft.

10 The operation of the apparatus is as follows: The controller-cylinder is brought to the open or off position by means of its handle. This brings the notch in the disk 51 opposite the latch 50, as shown in Fig. 2. The 15 multiple-voltage switch can now be set for the desired voltage, depending on the required speed. It is first pulled out of the notch in the side of the slot at the top of the casing. This presses back the pivoted plate 20 49 and pushes the latch 50 into engagement with the notch in the disk 51 on the controller-shaft. The controller is thus locked against movement and remains so until the 25 multiple-voltage switch-lever has been set for the desired voltage and has entered one of the notches in the side of the slot at the top of the casing. When it has entered one of the notches, the locking-plate follows and the spring-pressed latch with- 30 draws from the notch in the controller-disk, thereby releasing the controller. The controller can then be moved in either direction as desired; but when it is in any position except the open position the notch in 35 the disk is not opposite the latch and the multiple-voltage lever is locked against movement by the controller. It will thus be seen that the multiple-voltage switch is locked against movement away from the voltage connection to which it may be connected whenever the controller is turned from the open position, and the controller is locked against movement from the open position while the 40 multiple-voltage switch is being shifted from one voltage connection to the other. In other words, the multiple-voltage switch and the controller are interlocked by suitable mechanism.

What I claim as new, and desire to secure 50 by Letters Patent of the United States, is—

1. The combination with three or more con-

ductors having interconnecting means for maintaining them at different voltages, of a motor, a multiple-voltage switch and a controller between the motor and the conductors, and locking mechanism for the multiple-voltage switch which is operated by the controller and is released only when the controller is in open position, substantially as described.

55

2. The combination with three or more conductors having interconnecting means for maintaining them at different voltages, of a motor, a multiple-voltage switch and a controller between the motor and the conductors, and interlocking mechanism between the multiple-voltage switch and the controller, substantially as described.

60

3. The combination of a multiple-voltage switch and a controller, a notched guide-slot for the multiple-voltage switch-lever, a movable plate on the opposite side of the switch-lever from the notches in the guide-slot, a spring-pressed latch connected with the plate, and a notched disk carried by the controller, 70 by which the multiple-voltage switch is locked by the controller, substantially as described.

75

4. The combination with three or more conductors having interconnecting means for maintaining them at different voltages, of a motor with two field-coils, a switch for connecting one of the field-coils to two of the conductors, and a switch for shifting the connections of the other field-coil between the conductors, substantially as described.

85

5. The combination with three or more conductors having interconnecting means for maintaining them at different voltages, of a motor with series and shunt field-coils, a switch for connecting the shunt field-coil to two of the conductors, and a switch for shifting the connection of the series field-coil and armature between the conductors, substantially as described.
